UNITED STATES PATENT OFFICE

118,021

DESIGN FOR A COMBINED COMB, HAIR SMOOTHER AND WRENCH

Vincent R. Pileggi, Philadelphia, Pa.

Application September 11, 1939, Serial No. 87,133

Term of patent 7 years

To all whom it may concern:

Be it known that I, Vincent R. Pileggi, a citizen of the United States, residing at Philadelphia, in the county of Philadelphia and State of Pennsylvania, have invented a certain new, original, and ornamental Design for a Combined Comb, Hair Smoother and Wrench, of which the following is a specification, reference being had to the accompanying drawing forming part thereof.

In the drawing:

Fig. 1 is a side elevational view of a combined comb, hair smoother, and wrench showing my new design.

Fig. 2 is a front end elevational view thereof.

Fig. 3 is a rear end elevational view thereof.

I claim:

The ornamental design for a combined comb, hair smoother and wrench substantially as shown.

VINCENT R. PILEGGI.
